DESIGN FOR A SPOON OR SIMILAR ARTICLE

Grosvenor N. Allen and Mary G. Parker, Oneida,
N. Y., assignors to Oneida Community, Limited,
Oneida, N. Y., a corporation of New York

Application March 17, 1933, Serial No. 47,502

Term of patent 14 years

To all whom it may concern:

Be it known that we, GROSVENOR N. ALLEN and MARY G. PARKER, citizens of the United States, residing at Oneida, county of Madison, State of New York, have invented a new, original, and ornamental Design for a Spoon or Similar Article, fully described and represented in the following specification and the accompanying drawing, forming a part of the same in which—

Figure 1 is a plan view of a spoon or similar article showing our new design, and

Figures 2 and 3 are cross sections on an en-

larged scale on the lines 2—2 and 3—3, respectively, of Figure 1.

The essential feature of our new design is the configuration and ornamentation on the front face of the spoon or similar article.

We claim:

The ornamental design for a spoon or similar article as shown and described.

In testimony whereof we have hereunto set our hands.

GROSVENOR N. ALLEN,
MARY G. PARKER.
